UNITED STATES PATENT OFFICE.

THOMAS WILLIAM MORAN, OF LOUISVILLE, KENTUCKY.

REVERSIBLE STEAM-BOILER.

SPECIFICATION forming part of Letters Patent No. 672,795, dated April 23, 1901.

Application filed December 27, 1900. Serial No. 41,236. (No model.)

To all whom it may concern:

Be it known that I, THOMAS WILLIAM MORAN, a citizen of the United States, and a resident of Louisville, in the county of Jefferson and State of Kentucky, have made a certain new and useful Invention in Reversible Steam-Boilers, &c.; and I declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a transverse vertical section through my boiler. Fig. 2 is a top plan view of the same with the cover removed and head partly broken away. Fig. 3 is a section of my fusible-plug device. Fig. 4 is a detail 20 plan view of the steam-coil.

The invention relates to steam-boilers, and particularly to an upright cylinder type intended to be used for fire-engines, steamboats, automobiles, and locomotives, although it 25 may be applied wherever a powerful and efficient steam-generator is needed.

The invention consists in the novel construction and combinations of parts, as hereinafter set forth.

30 In the accompanying drawings the letter A designates one head of the boiler; B, the other head; C, the side wall, and D D the flues.

E is a large central flue-pipe which forms a tie, serving as a stay for the head-plates in 35 their central or weakest portions. The heads or head-plates are usually formed with circumferential flanges a and b, which extend outward and are somewhat flared in order to provide an interspace, as at a' and b', between 40 the flanges and the side wall. These heads are preferably of similar form and construction, the head A being provided with an opening at e for the smoke-flue, another at e' for the exit of the steam-pipe connection to the

45 steam-chest, and a third, e'', for the attachment of a steam-gage. The head B is provided with similar openings f for the entrance of a gas or vapor pipe to the burner f' for the water-feed and mud-valve and f'' for convenience in reversal. These head-plates being flanged, as stated, form similar chambers, the lower one, I, serving as a fire-box and the

upper one as a superheating-chamber K, in which is located the steam-coil G. In the fire-box is indicated a burner F, which is provided with a perforated bottom plate h, which is formed with a flange for attachment to the lower edge of the boiler. The steam-coil chamber K is provided with a cover L, which is attached to the upper edge of the boiler. 55 This cover L as well as the side wall of the boiler is packed with asbestos and closed in with sheeting of Russia iron. The cover L and the burner F are secured in position by means of screws m, and when these are removed and the fuse-plug tube and steam-coil and other attachments are disconnected the boiler proper, with the fire-box and the steam-coil chamber, all being in one, can be detached from the jacket and reversed, the upper head 60 A being transferred to become the fire-box, while the head B is changed to the top of the boiler and becomes the steam-coil chamber. The pipe attachments being put in position, the boiler is ready for operation again. This 65 reversal can be made in a short time and serves an important purpose in extending the life of the boiler.

The central flue-pipe E extends through openings d and d' in the upper and lower 70 heads, and its ends are threaded for the nuts c, whereby it is secured in position. The upper nut c engages the shouldered thimble t, which engages, by means of its shoulder, the upper head-plate. This thimble t is provided 75 with an opening t', which is threaded for the reception of the inner end of the steam-coil pipe G, the turns of which are usually arranged to form an inverted cone, the inclination of which causes water of condensation to 80 pass back into the boiler, besides having a 85 larger heating-surface.

In order to increase the heating effect of the flues D D, they are somewhat inclined in opposite directions in such a manner as to 90 provide a staggered arrangement. To this end the flue-pipes of one circle are inclined in one direction with reference to their radial planes, while those of the next circle are inclined in the opposite direction. These inclined flues are designed to generate more steam than would be the case if they were perpendicular to the planes of the boiler-heads, not only on account of their greater 95 100

amount of heating-surface, but also because the currents of the heated particles will, in a manner, intersect the flues and the circulation will be increased. These double inclined flues also brace the heads of the boiler together.

P indicates the extension fusible-plug device, which consists of a pipe *p*, having in its upper end the fusible plug *p'*, this pipe 10 being connected to the thimble *s*, which is screwed into a threaded opening in the lower head-plate. In this pipe, at its lower end, are openings *n*, controlled by the valve *V*, the stem of which has an adjustable screw engagement with the pipe *p*. The lower openings *n* serve to allow the melted metal of the plug to run out. The object of the valve is to enable the operator to close the pipe for running purposes after the safety-plug has 15 been melted in serving its end.

This boiler is designed to be neat and compact, requiring but little space in comparison with its power and efficiency. It is very strong, the fire-box, breeching, and boiler being all three in one structure.

When the lower head becomes incrusted or coated on its inner or water side with scale or deposit of non-conducting material, so that the boiler does not make steam as readily and 20 quickly as it should, the pipe-unions may be unscrewed and the boiler reversed—that is, turned end for end—and reconnected in a short time—about thirty minutes—and then the boiler will work as well as a new one, as 25 it is perfectly clean in the new water-space end; and in the steam end the deposit will be gradually removed.

The reversible central flue-pipe may be made large enough to be used as a flue or 30 dome stack to carry off the products of combustion from the furnace and liberate them in the open air underneath a steam-carriage, the exhaust being used for artificial draft, if necessary. This flue or tube, made large and 35 strong, acts as a mainstay to hold the crown-sheets *A* and *B* securely intact at the center, which would otherwise be the weakest point.

The valve may, if desired, be carried in the tool-box of the carriage, and when the 40 fuse-plug melts out, if there is occasion for haste, the valve may be used to plug the boiler, thus enabling the operator to refill

the boiler, raise steam, and proceed on the journey.

Having described this invention, what I 55 claim, and desire to secure by Letters Patent, is—

1. A reversible steam-boiler, having its heads of exactly similar pattern for interchangeable connection with pipe attachments, substantially as specified.

2. In a reversible-cylinder steam-boiler, the central flue-pipe engaging the central reversible portions of the head-plates, and the removable superheating-coil having a connection with said flue-pipe, substantially as 60 specified.

3. In a steam-boiler, the reversible structure, comprising the boiler proper and its exactly similarly flanged end chambers for 70 fire-box, and breeching purposes, substantially as specified.

4. In a steam-boiler, the combination with the jacket, of the reversible boiler proper, its end flanges forming the fire-box, and breech-chamber, the central tie-flue, the removable burner and the removable superheating-coil, 75 substantially as specified.

5. In a steam-boiler, the combination with the reversible boiler proper, and its end 80 flanges forming the fire-box and breech-chamber, of a central tie-flue, a removable burner, a removable superheating-coil, and a removable fusible-plug extension-tube, substantially as specified.

6. In a steam-boiler, the combination with the side wall and the similar outwardly-flanged head-plates of the oppositely-inclined or staggered flues, and the central tie-flue, 85 substantially as specified.

7. A reversible-flue boiler, having similar head-chambers, a removable superheating-coil in one, and a removable burner in the other, a removable center tie-flue a shoddered thimble connected to the superheating-coil, and an extended fusible-plug pipe having a valve, substantially as specified.

In testimony whereof I affix my signature in presence of two witnesses.

THOMAS WILLIAM MORAN.
